UNITED STATES PATENT OFFICE.

FLOYD McCCLURE, OF HUNTERSVILLE, NORTH CAROLINA.

VENDING MACHINE.

Application filed January 4, 1927. Serial No. 158,886.

This invention relates to a machine designed primarily for vending bottles containing soft drinks, one of the objects being to provide a receptacle for a refrigerant in which the bottle holding mechanism is located, coin controlled means being employed whereby the bottle holding mechanism can be released for actuation to deliver a single bottle.

10 A further object is to provide a structure of this character which is simple and compact in construction, formed of the minimum number of parts, and is capable of extension so that the number of bottles that can be stored 15 at one time within the apparatus can be practically without limit.

A further object is to provide simple and efficient means for indicating the number of bottles remaining in the apparatus.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed may be made within the scope of what is claimed, without departing from the spirit of the invention.

30 In the accompanying drawings the preferred form of the invention has been shown.

In said drawings,

Figure 1 is a front elevation of the apparatus.

35 Figure 2 is a section on line 2—2, Figure 1.

Figure 3 is a vertical longitudinal section showing the interior mechanism in elevation, a part of one of the bottle carrying wheels being broken away and one of the bottles being shown in the act of being delivered.

40 Figure 4 is a front elevation of the mechanism within the housing of the machine, said housing being shown in section.

Figure 5 is a section through the coin carrier, the actuating disk cooperating therewith being also shown.

Referring to the figures by characters of reference 1 designates a housing of any desired proportions which can be provided, at 50 one side of the back thereof, with a compartment 2 adapted to receive empty bottles. Ice used for cooling the contents of the housing can be inserted into a space 3 provided at one side of the empty bottle receptacle and 55 opening downwardly into the housing.

A transverse shaft 4 is mounted for ro-

tation within the housing 1 and secured to this shaft so as to rotate therewith is a bottle conveying and holding wheel made up of spaced disks 5 and 6 connected at regular 60 intervals by cross strips 7. Thus bottle receiving cells 8 are provided in the wheel, these cells being arranged in an annular series. The hub 9 of the wheel, located between the disks 5 and 6, constitutes an abutment for 65 the inner ends of the bottles seated in the cells, as shown particularly in Figure 3. One of the disks 5 of the wheel constitutes a gear, the said gear (disk 5) meshing with a small gear 10 secured to a transverse shaft 11. A 70 disk 12 is also secured to the shaft 11 and is provided at regular intervals with blocks 13 each of which constitutes a coin receiver, each block having a flared opening 14 in the outer end portion adapted to deliver a coin inwardly into a slot 15 opening through the bottom of the block. A disk 16 is journaled on the shaft between the blocks 13 and has a radial shoulder 17 adapted to work within slots 18 formed in the inner ends of the blocks 13 and 75 intersecting the slots 15. A sleeve 19 rotates with the disk 16 and has a lever 20 fastened thereto, this lever being extended through a slot 21 in the front wall of the housing 1 and being normally supported yielding by a 80 spring 22. Slot 21 is of such length as to properly limit the rotation of the disk 16 so that during each complete downward movement of lever 20 within the slot 21, the shoulder 17 will be rotated a distance equal 85 to the distance between two adjoining blocks 13. A coin chute 23 opens through the front wall of the housing 1 and is inclined downwardly to a point close to the path of the outer ends of the blocks 13. The lower end of this 90 chute is so located that when the blocks are at rest, one of them will be positioned to receive a coin within the flared opening 14, as shown particularly in Figure 3. It will be noted that the marginal portion of the disk 100 16 works within the slots 18 in the inner ends of the blocks. Consequently these slotted ends of the blocks constitute means for holding the disk 16 properly assembled relative to the disk 12 so that the parts are maintained 105 in proper operative relation without requiring the use of any additional means for this purpose.

A spool 24 having a tape 25 rolled thereon is mounted within the housing close to the 110 front wall thereof and near a sight opening 26 in the wall. The tape is extended across this

opening and over guide rollers 27 to a winding wheel 28 carried by the shaft 4. On this tape are numbers arranged consecutively from "1" upward, these numbers indicating the number of cells in the wheel carrying the bottles. For example if there are twenty cells in the wheel, the numbers will range from 1 to 20 and they are so spaced apart that each time the wheel is given a partial rotation as hereinafter explained, a number will appear in the opening 26 to indicate how many bottles remain in the housing.

A coin receiver 29 is located below the coin carrying wheel and arranged outside of the lower portion of the housing is a bottle receiver 30. An opening 31 communicates with this receiver and is normally closed by an outwardly swinging door 32. An arcuate retaining plate 33 is arranged beneath the bottle carrying wheel so as to retain bottles in the lower portion of the wheel and this plate extends up to an inclined plate 34 extending downwardly to the bottom of the opening 31.

In practice the cover 35, of the housing 23 is raised and bottles are placed successively within the cells 8, these bottles being indicated at B. The spool 24 can be spring controlled like a curtain roller so as to automatically wind the tape 25 thereon when the bottle containing wheel is rotated backwardly during the filling operation. Thus after all of the cells 8 have been filled the numeral appearing in the opening 26 will indicate the entire number of bottles in the housing.

When it is desired to dispense a bottle a coin of the proper value is inserted into the chute 23 and will slide into the flared opening 14 of the block at the lower end of the chute. The coin will gravitate into the slot 15 and assume a position across slot 18, the lower portion of the edge of the coin resting on the periphery of the disk 16 close to and in front of the path of the shoulder 17. The customer then depresses lever 20 so as to cause the disk 16 to rotate. Consequently shoulder 17 will come against the projecting portion of the coin which thus serves to lock the disk 16 to the coin carrying wheel. Therefore the coin carrying wheel will be moved to carry the coin from its upper position to an intermediate position, this movement being sufficient to rotate shaft 11 and gear 10 so as to bring one of the bottle containing cells to position above the chute 34. Consequently the bottle

in said cell will gravitate along the chute and against the door 32. The door will open and the bottle will drop into the receiver 30. When the lever 20 is released it will be returned by the spring 22 to its normal position and the shoulder 17 of disk 16 will assume a position adjacent the next block 13 which has been brought to position under the lower end of chute 23. Should lever 20 be depressed without first inserting a coin, there would be no operation of the mechanism because a coin

is necessary to couple disk 16 to the coin carrying wheel and to the shaft 11. As the mechanism is operated by the subsequent insertion of a coin and actuation of the lever, the coin previously inserted will be brought to position where it will gravitate from the block 13 into the coin container 29. Each time the bottle carrying wheel is given a partial rotation the number appearing in the opening 26 will be changed to indicate the total number of bottles remaining in the apparatus.

In the apparatus shown three bottle carrying wheels have been illustrated, these being arranged side by side on the shaft 4 and indicated generally at X, Y and Z. The wheels are all of the same construction with the exception that the first wheel X has one of its disks in the form of a gear as shown at 5 whereas the wheels Y and Z do not have gears 85 forming portions thereof. Extending laterally from the wheels are projecting lugs 36 so located that as the last bottle is delivered from the wheel X, the lug 36 on said wheel comes against one of the lugs 36 on the wheel Y so that further rotation of the shaft 4 in the manner heretofore explained will result in the transmission of motion from wheel X to wheel Y and, consequently, the first bottle contained in wheel Y will be delivered on to the chute 34.

After the wheel Y has been emptied one of the lugs 36 thereon will come into engagement with one of the lugs or projections 36 on the wheel Z with the result that wheel Z 100 will then begin to empty its bottles, one at a time by the operation of the mechanism described. Obviously the number of wheels can be increased so as to give the apparatus any desired capacity.

Furthermore where different kinds of beverages are to be dispensed separate groups of dispensing mechanisms can be located in one housing, each group, however, being provided with independent coin controlled 110 mechanism and operating means. Such an arrangement is so obvious that it is not deemed necessary to show or describe the same in detail.

What is claimed is:

In a vending machine the combination with a housing and a bottle conveying member, of a gear movable with said member, a drive gear meshing therewith, a shaft on which the drive gear is mounted, a disk secured to said shaft, laterally extending blocks on the disk at regular intervals, each block constituting a coin receiver, there being a flared opening in the outer end of each block and a coin receiving slot in the block communicating with the opening, the inner end of each block being formed with a slot extending therethrough at right angles to the coin receiving slot in the block, a sleeve mounted for rotation on the shaft, a disk revoluble therewith

having a radial shoulder adapted to travel within the slots in inner ends of the block, said disk having a cam edge extending there-around from the outer end of the shoulder to the inner end of the shoulder, a lever extending from and adapted to actuate the sleeve and disk, and means for directing a coin into any one of the blocks when brought

to a predetermined position, the slots in the inner ends of the block cooperating with the marginal portion of the shouldered disk to hold said disk properly assembled relative to the block.

In testimony that I claim the foregoing as my own, I have hereto affixed my signature.

FLOYD McClURE.
